CLAIM

The ornamental design for an electrical conductor as shown
and described.

DESCRIPTION

FIG. 1 is a perspective view of an electrical conductor.

FIG. 2 is a zoomed-in view of a portion of the electrical
connector of FIG. 1.

FIG. 3 is a top view of the electrical conductor of FIG. 1.

FIG. 4 is a bottom view of the electrical conductor of FIG.

1.

FIG. 5 is a first side view of the electrical conductor of FIG.

1.

FIG. 6 is a second side view of the electrical conductor of FIG.

1.

FIG. 7 is a first end view of the electrical conductor of FIG.

1; and,

FIG. 8 is a second end view of the electrical conductor of FIG.

1.

Those portions of the present invention which are presented
in “dashed” (i.e., “---”) broken lines represent the environment
of the design only and form no part of the claimed
design. The “dot-dash-dot” (i.e., “----”) broken lines define
the boundary of the claimed design and form no part thereof.
Moreover, any surface shading presented in the accompa-
nying drawings is provided merely to highlight the contour
of the invention and is not intended to be illustrative of
texture or gloss of the claimed design. The broken line
circling FIG. 2 is included to show the boundary of an
enlarged view that forms no part of the claimed design.

1 Claim, 3 Drawing Sheets
